UNITED STATES PATENT OFFICE.

CHARLES G. MINOR, OF DULUTH, MINNESOTA.

SPARK-PLUG.

1,397,535.

Specification of Letters Patent. Patented Nov. 22, 1921.

Application filed March 25, 1920. Serial No. 368,502.

To all whom it may concern:

Be it known that I, CHARLES G. MINOR, a citizen of the United States, residing at Duluth, in the county of St. Louis and State 5 of Minnesota, have invented certain new and useful Improvements in Spark-Plugs, of which the following is a specification, reference being had therein to the accompanying drawing.

10 This invention relates to spark plugs for internal combustion engines and has for its principal object improvements over those at present known in the art.

Another object is simplicity of construction.

Still other objects and advantages of the peculiar structure will appear in the further description of the invention.

Referring to the accompanying drawings 20 forming part of this application and in which like reference characters indicate like parts:

Figure 1 is a central vertical sectional view partly in elevation of one of my improved plugs, and

Fig. 2 is a lower end plan view.

Broadly, the invention resides in incasing both of the electrodes 1 and 2 of the spark plug within the porcelain or insulated core 30 of the plug, and making the lower portion of the core, which extends within the lower end of the plug casing 4, as large as possible consistent with sufficient clearance to care for expansion et cetera, as well as making the lower end of the porcelain extend somewhat beyond the lower end of the plug, as clearly seen in the drawings.

The core 3 is provided with the usual annular shoulders 5 and 6 and which is held 40 in place within the casing by the usual screw threaded gland 7. The upper end 8 of the electrode 2 which is the shorter one, terminates in the shoulder 5 of the core and is impinged by the lower beveled edge of the gland 7 when the latter is screwed in place, thus completing the grounding circuit of the plug, while the electrode 1 extends the full

length of the porcelain and is engaged at the upper end with the usual thumb nut. As before stated the lower end of the core 50 extends beyond the lower end of the casing and the ends of the electrode project beyond the porcelain, they being each turned at right angles toward each other and one above the other as shown in 55 Fig. 1 whereby the spark may occur either intermediate of the end of the shorter terminals and the vertical portion of the opposite electrode or between the two horizontal portions of the terminals, and the gap may 60 be adjusted in the usual way by bending of either or both of the terminals.

Each electrode is surrounded by a conically shaped portion of the porcelain indicated at 10 as a preferred form of the structure, which is found to assist in quickly heating the terminals and thus preventing the collection of oil on the electrodes at the time of starting a cold engine.

The inner lower edge of the plug is beveled as at 11 to further concentrate heat about the end of the core and insure non-fouling of the terminals.

Having thus described my invention, what I claim and desire to secure by Letters Patent, is:

The combination with a spark plug of the character described including a casing, a core and a holding gland, of two electrodes incased within the core and extending beyond the lower end thereof and the ends of both electrodes being bent inwardly toward each other and one above the other, whereby the spark may occur either intermediate of the end of the shorter terminals and the 85 vertical portion of the opposite electrode or between the two horizontal portions of the terminals, substantially as described.

In testimony whereof I hereunto affix my signature in the presence of two witnesses.

CHARLES G. MINOR.
